UNITED STATES PATENT OFFICE.

CHARLES H. DAVIS, OF WORCESTER, MASSACHUSETTS.

DENTAL-ENGINE HANDPIECE-COUPING.

SPECIFICATION forming part of Letters Patent No. 543,854, dated August 6, 1895.

Application filed May 13, 1895. Serial No. 549,160½. (No model.)

To all whom it may concern:

Be it known that I, CHARLES H. DAVIS, a citizen of the United States, residing at Worcester, in the county of Worcester and State of Massachusetts, have invented a new and useful Improvement in Dental-Engine Handpiece-Couplings, of which the following is a specification, reference being had to the accompanying drawings, forming a part of the same, and representing a handpiece-coupling for dental engines embodying my invention.

Figure 1 of the drawings represents a portion of the flexible shaft and handpiece united by one of my improved couplings, shown in side view. Fig. 2 is a vertical central sectional view of my improved coupling, showing so much of the handpiece and flexible shaft as is necessary to illustrate the subject-matter herein claimed. Fig. 3 is a perspective and 20 detached view of the barrel, which is attached to the handpiece and adapted to receive an elastic sleeve. Fig. 4 is a perspective and detached view of the elastic sleeve, which is connected with the flexible shaft and adapted to 25 slide over the barrel shown in Fig. 3. Fig. 5 is a perspective and detached view of the triangular shank, which is connected with the tool-driving spindle. Fig. 6 is an end view of the same, and Fig. 7 is a perspective and 30 detached view of the rotating spindle, which is driven by the flexible shaft, the coupling-sleeve in which the spindle is journaled, and the elastic or spring jaws formed upon the end of the driving-spindle and adapted to 35 close the triangular shank which is shown in perspective view in Fig. 5.

Similar letters refer to similar parts in the different figures.

My invention relates to an improved slip-joint or coupling between the ends of two rotating spindles having their axes in alignment and also between the ends of tubular casings enclosing the rotating spindles, and it is especially applicable in forming a slip-joint or 45 coupling connection between a handpiece and the driving-shaft of a dental engine.

Referring to the accompanying drawings, and particularly to Fig. 2 of the drawings, A denotes a portion of the covering of a flexible shaft screwed upon the rear end of a coupling-sleeve B, forming a bearing for the rotating spindle C, which is journaled in the sleeve B

and held from longitudinal movement by means of a shoulder C', formed in the spindle C, and a collar C², attached to the spindle, said shoulder and collar bearing against the ends of the sleeve.

The rear end of the rotating spindle C is operatively connected with and driven by the flexible shaft, and the forward end of the spindle C is provided with elastic jaws C³, preferably three in number, and their inner faces C⁴ forming a central chamber adapted to receive an angular shank D, preferably triangular, having its sides D' fitting the inner faces C⁴ of the elastic jaws C³.

The shank D is provided with an internal screw-thread D² and is held upon a screw-threaded section E' of the spindle E, which is journaled in the handpiece F and operatively connected with the tool in the usual manner in instruments of this class. The shank D has its end beveled or tapered, as at D³, so it will enter readily between the elastic jaws C³ and also serve as a wedge to slightly separate the elastic jaws in order to cause the faces C⁴ of the jaws to pinch against the sides D' of the shank and produce a tight fit between the jaws and shank. The handpiece F is screw-threaded at F' to receive a barrel G, which is reduced in size at G', forming a shoulder G² and having at the base of the shoulder G² a shallow annular groove or channel G³. The end of the barrel G is slightly tapered upon its outer surface, as at G⁴, to enable it to readily enter within a sleeve H, which is screwed upon the front end of the coupling-sleeve B.

The sleeve H is split at H', forming elastic sections H², provided at their free ends with a slightly-raised rib H³, adapted to enter the shallow groove G³ in the barrel G. The barrel G and the sleeve H form tubular extensions of the handpiece F and flexible shaft A, which overlap each other, forming a telescopic joint as the shank D is carried between the elastic jaws C³. The outer diameter of the reduced section G' of the barrel G throughout about half its length from the shoulder G is preferably made slightly larger than the interior diameter of the elastic sections H', so that when the two parts are united the elastic sections H' will be slightly separated and made to pinch upon the outer surface of the section G', so as to produce a tight fit and al-

low the elasticity of the sections H' to compensate for any wear between the surfaces in contact, and also to produce sufficient frictional resistance between the section G' and the elastic sections H' to resist the rotation of the barrel G within the sleeve H. As the tapered end G⁴ of the barrel is entered between the free ends of the elastic sections H they will be crowded apart until the ends of the sections H' abut against the shoulder G², when the ribs H³ will snap into an annular groove G³, locking the two parts together. The inner edge of the ribs H³ and the corresponding opposing wall of the shallow groove G³ are made slightly beveled in order to cause the sections H' to be crowded outward when sufficient force is applied to draw the barrel G out of the sleeve H.

When the handpiece and flexible shaft are coupled together with my improved coupling, the ends of the sections H' are brought against the shoulder G² of the barrel G in order to cause the ribs H³ to engage the groove G³; but as the portion of the spindle E which projects beyond the handpiece may vary in length in different handpieces I make the sides D' of the shank D of sufficient length to allow for such variation in the handpieces, causing the shank D to enter farther between the elastic jaws C³ by an increase in the length of the spindle E.

By the above-described construction I secure a clutching device between the two spindles C and E by means of a shank D held concentrically with the spindle E and entering a central chamber between the elastic jaws C³, causing the shank D to be rotated by the contact of the faces C⁴ of the spindle C with the sides D' of the shank.

Each of the jaws C³ is capable of yielding to accommodate any error of alignment between the jaws and the shank D, and when the two are engaged the jaws are slightly wedged apart by the action of the tapering end G⁴, so the elasticity of the jaws serves to hold the faces D⁴ in close contact with the sides D' of the shank, and the two parts of the coupling are held from separation while

in ordinary use by the elastic sections H' of the sleeve, which hold the ribs H³ in engagement with the groove G³, thereby doing away with a separate latching device.

It will be observed that both joints—viz., that between the spindles C and E and that between the inclosing casings, consisting of the sleeve H and barrel G—are telescopic joints, comprising a male and female part, and that one half of each joint is made elastic, so as to be expanded by its engagement with the other half of the joint, so that any variation in the alignment of the several parts is provided for and tight fit is secured between all the surfaces in contact.

What I claim as my invention, and desire to secure by Letters Patent, is—

1. In a coupling for dental engines, the combination of the barrel G provided with an annular groove G³, and an inclosing split sleeve having elastic sections H', and ribs H³ adapted to engage said annular groove G³, substantially as described.

2. In a coupling for dental engines, the combination of the rotating spindle C provided with elastic jaws C³, having faces C⁴ forming a central chamber adapted to receive an angular shank, a spindle E and an angular shank D having sides D' and a tapered end D³ and carried by said spindle and arranged to enter said elastic jaws, substantially as described.

3. A coupling for dental engine hand-pieces comprising a two-part spindle having their axes in alignment and detachably united by a telescopic joint, and a two-part casing, wherein said spindle is journaled, also detachably united by a telescopic joint, said joints being of such construction that one part thereof is elastic and capable of expansion by the entry therein of the other part, whereby the same are held in place and provision is made for variation in alignment of the parts, substantially as described.

CHARLES H. DAVIS.

In presence of—

RUFUS B. FOWLER,
EMMA KESTER.
